PUNCH

James K. Duncan, Park Ridge, and William H. Dreyer, Skokie, Ill., assignors, by mesne assignments, to American Photocopy Equipment Company, Chicago, Ill., a corporation of Illinois

Filed Aug. 2, 1957, Ser. No. 676,028

3 Claims. (Cl. 83—549)

The present invention relates to sheet punching apparatus and more particularly to a manually operated punch for forming binding holes in a stack of paper sheets.

It is the general aim of the invention to provide a novel punching apparatus having an array of punches which may be selectively conditioned for forming a desired pattern of punched holes in a stack of sheets. In more detail, it is an object to provide an apparatus with a punch array mounted in a common actuator with individual disabling means of a novel type for each punch so that individual punches can be quickly and conveniently selected for operation, or disabled, making the apparatus completely flexible in operation. It is a related detailed object to provide a punch array with a disabling means of novel design for each punch which can be easily positioned with a detenting action for selective disabling individual punches without removing parts from the apparatus.

It is also an object to provide a punching apparatus having an array of punches of novel construction permitting cyclic or "staggered" operation of the punches both in cutting into, and withdrawing from, the work so that a smooth shear-like punching action is obtained. It is a related object to mount the punches of an array in a novel manner permitting economical replacement and convenient servicing.

It is a further object to provide a punch and die apparatus with a novel punch support and guiding structure which is strong, rigid, smooth in operation, and economical to manufacture.

Other objects and advantages of the invention will become apparent upon reading the attached detailed description and upon reference to the drawings in which:

Figure 1 is a front elevation view of a punch constructed according to the present invention with its protective cover removed.

Fig. 2 is an end view of the punch shown in Fig. 1 with the end portion of the punch cover broken away.

Fig. 3 is an enlarged, fragmentary, sectional view of a portion of the punch shown in Fig. 1.

Fig. 4 is a plan view of a single punch sub-assembly of which three are incorporated in the punch shown in Fig. 1.

Fig. 5 is a front elevation view of the punch sub-assembly shown in Fig. 4.

Fig. 6 is a fragmentary plan view showing a rear work positioning stop utilized in the punch illustrated in Fig. 1.

Fig. 7 is similar to Fig. 3 and shows a punch disabled and the punch block in its lower position.

Fig. 8 is similar to Fig. 5 and shows the punches in the sub-assembly following the punching operation and prior to withdrawal of the punches from the work.

While the invention will be described in connection with a preferred embodiment, it will be understood that we do not intend to limit the invention to that embodiment. On the contrary, we intend to cover all alternatives, modifications and equivalents as may be included

2

within the spirit and scope of the invention as defined by the appended claims.

Turning first to Figs. 1 and 2, there is shown a punch 10 embodying the invention which includes a work supporting table 11 and a protective cover 12, shown partially broken away in Fig. 2, which encloses the punch mechanism. At the intersection of the table 11 and the housing 12 there is located a work receiving throat 13 defined by an upwardly flared, rigid, hold-down bar or stripper 14 which closely overlies the end of the table 11 (see Fig. 3).

In order to punch a spaced row of holes along the edge of a sheet positioned in the throat 13, an array of punches 15 is reciprocably mounted within the cover 12 and aligned over a corresponding series of die openings 16 formed in the table 11. The punches 15 are adapted to vertically reciprocate into and out of the die openings 16 to perform their punching function in the conventional manner. Guiding the punches in their vertical movement are apertures 17, formed in the hold-down plate 14, and apertures 18 formed in a second plate 19 that is supported at a fixed distance above the hold-down plate.

The entire array of punches 15 is supported and actuated by a punch block 25 extending transversely across the apparatus and over the throat 13. Each of the punches 15 is suspended within its respective guide apertures 18, 19 by means of a projecting pin 28 carried by each punch and which rests upon a pair of inturned opposed ledges 26, 27 forming part of the punch block 25.

The punch block 25 is mounted for vertical movement on a pair of spaced H-shaped slides 31, 32 (see Figs. 1 and 2) whose opposite legs straddle and reciprocate relative to a pair of crossbars 33, 34 which are flat-sided in cross-section. The crossbars are fixed between upstanding frame plates 35, 36, which in turn are mounted on the table 11 by means of screws 36a. In the present embodiment, bearing insets 37 are secured to the opposite inner sides of the legs formed on the H-shaped members 31, 32 in flat engagement with the crossbars 33, 34 so as to provide a low-friction, sliding connection between the H-shaped members and the crossbars.

To reciprocate the punch block 25, and thus actuate the punches 15, a pair of radial cams 41, 42 are rotatably secured to the H-shaped members 31, 32 and adapted to cooperate with respective pairs of rollers 45, 46 and 47, 48 journaled in fixed position on the supports 35, 36. In the illustrated apparatus the cams 41, 42 are non-rotatably secured to a shaft 43 which is journaled by means of roller bearings 34 within the H-shaped members 31, 32. The roller pairs 45, 46 and 47, 48 are journaled by means of suitable bearings on extension shafts at the opposite ends of the shafts 33, 34 (see Fig. 1).

The cams 41, 42 are similar in configuration and are so designed that rotation of the shaft 43 counterclockwise in Fig. 2, will cause the cams 41, 42 to bear against the upper rollers 45, 47 respectively, and thus force downwardly the H-shaped members 31, 32 carrying the punch block 25. Return rotation of the shaft 43 will cause the cams 41, 42 to bear against the lower rollers 46, 48 and thus move upwardly the H-shaped members 31, 32 and the associated punch block structure.

To permit the shaft 43 to be conveniently rotated by manual force, a handle 50 is non-rotatably secured to one end of the shaft 43. It will be understood that an operator may reciprocate the punch block 25 by grasping the handle 50 and rotating it forwardly and toward the table 11.

In keeping with the present invention, the punches 15 are mounted for limited lost-motion movement relative to the punch block 25 and a positionable blocking pin is provided for each punch to prevent lost-motion move-

ment when the punch block is reciprocated. In the present embodiment, the blocking pins are slidable between a withdrawn position allowing a punch to remain idle when the punch block is reciprocated, and a blocking position preventing lost-motion punch movement and causing the punch to operate when the punch block is reciprocated. In this way, selective operation of each of the punches 15 in the punch array is obtainable.

In order to provide lost-motion movement of the punches 15, the punch block 25 is formed of a series of plates secured together with a central plate 51 being of lesser height than the adjoining plates 52, 53 so as to define a slot 54 extending along the punch block directly above the array of the punches 15.

To prevent lost-motion movement of the punches 15 up into the slot 54 when the punch block is reciprocated, each punch is associated with an overlying blocking pin 55 which is slidable in apertures formed in an outer punch block plate 56 and a bracket 57 having a Z-shaped cross-section and which is secured to the plate 56. Each pin 55 is closely aligned with the bottom of the plate 52 and a ledge 58 formed on the plate 53. Thus, when a pin 55 is slid inwardly and over a punch 15, the reactive punching force exerted by the punch against the pin as the punch block is reciprocated will be transmitted directly to the ledge 58 and the bottom of the plate 52 without tending to deform the pin.

In order to selectively retain the pins 55 in either their inserted position, wherein they block the slot 54, or their withdrawn position, where they permit the associated punch to idly move into the slot, a detent arrangement 60 is provided for each blocking pin. In the present embodiment, the detents 60 include a ball 61 partially recessed into the under-surface of a pin 55 and a bent spring leaf segment 62 which resiliently bears upwardly against the ball. Each of the segments 62 are preferably formed as integral fingers on a plate 63 that is clamped between the plate 56 and the bracket 57. It can be seen by comparing Figs. 3 and 7 that each spring leaf 62 will releasably retain a pin 55 in either its fully inserted or fully withdrawn position. It will also be noted that the pins 55 are at all times held captive and are not removed to disable their associated punches. Thus, there is no opportunity for the pins to become misplaced or lost.

Further in carrying out the invention, the punches 15 are proportioned and arranged in sub-assemblies so that the operation of the punches will not be simultaneous, but rather the punching action will proceed in waves along the work somewhat in the manner of a shearing operation so that less force is required to form a series of punched holes and a smoother operating cycle is achieved. In the machine of the illustrated embodiment, the array of punches 15 is subdivided into three identical sub-assemblies 71, 72 and 73 (see Fig. 1). Each of the sub-assemblies 71-73 includes a series of the punches 15 which are of varying length and arranged in stepped relation (see Figs. 4 and 5).

In the preferred arrangement, the centermost punch is the tallest in each sub-assembly and progressively shorter punches are located on either side of the tall center punch. It can thus be seen that as the punch block 25 is brought downwardly by operating the handle 50, the centermost punch in each sub-assembly will be the first to perform its punching function with the punches on either side of the center punch operating successively thereafter. The punching action is thus shear-like, the cutting starting at a single point and spreading outwardly from that point.

It has been found that in operating a punching apparatus of the type disclosed, as much force is required to withdraw the punches from the work as is required to initially punch the work. The spacing of the pins 28 from the top of the punches is thus varied so that the withdrawing force is smoothly and successively applied to each of the punches 15. It can thus be seen that the punch

with its support pin 28 farthest from the top will be the first one lifted from the work when the punch block 25 is drawn upwardly following the punching operation. In the illustrated machine, the center punch of each of the 5 punch sub-assemblies 71-73 has its pin 28 farthest from the top of the punch, with the punches on either side having their pins progressively closer toward their tops. Thus, as can be seen in Fig. 8, upward movement of the punch block 25 will cause the center punch in each of 10 the sub-assemblies to be the first withdrawn from the work followed by the successive withdrawal of the punches to either side of the tall center punch.

In addition, by mounting the punches in separate sub-assemblies, replacement of worn or damaged parts becomes more convenient and economical since the punches 15 are handled in small groups.

A further feature of the invention is the provision of a rear work positioning stop that is shiftable laterally of the machine 10 and provided with cams to vary its effective back-stopping position in accordance with its lateral setting. In the present embodiment, the rear work positioning stop comprises an elongated bar 80 slidable laterally at the rear of the throat 13. The bar 80 is provided with a cam plate at each end, 81 and 82 respectively, with 20 the cam plate 82 being formed with an upwardly turned flange 83 that provides a convenient handle for shifting the bar 80 laterally of the work supporting table 11. The cam plates 81, 82 are provided with parallel cam slots, 84, 85 respectively, which are diagonally disposed 25 with respect to the bar 80 and which engage cam followers 86 that are secured to the table 11 and pass through the cam slots. It is thus be understood that as the bar is shifted laterally the fixed cam followers 86 will engage the diagonal cam slots 84, 85 and cause the stop bar 80 to move longitudinally of the machine 10.

To aid in properly locating the bar 80, a spring-biased 30 detent 88 is mounted within the surface of the table 11 (see Fig. 1) and cooperates with any one of a series of grooves 89 formed in the underside of the cam plate 82 (see Fig. 6). A pointer 91 and gauge plate 92 may also be provided to indicate to the operator the position in 35 which the bar 80 has been placed.

To assist in positioning the work an adjustable side 40 guide 96 is mounted on the table 11 and provided with a thumbscrew 97 effective for locking the guide 96 in a desired adjusted position.

For the purpose of receiving the scrap material punched from the work, a tray 93 is slidably mounted on ways 45 94, 95 (see Fig. 1) for movement beneath the work supporting table 11 and to a position underlying the die openings 16. It will thus be apparent that the scrap punched from the work by the punches 15 will be deposited directly downwardly into the tray 93 and that the tray may be slid from beneath the table 11 to be conveniently 50 emptied.

We claim as our invention:

1. In a punching apparatus, a punch structure comprising, in combination, a punch block having a ledge, an array of punches slidably mounted in said block adjacent said ledge so that each punch may reciprocate upwardly into said block, each of said punches having a lateral projection to engage said ledge and thus limit downward movement of the punch relative to the block, a series of blocking pins slidable in said punch block and positioned 55 so that one pin may be disposed over each of said punches to limit upward movement of the punch relative to the block, said punches being of regularly varying length so that upon downward movement of the punch block the punches in the array will successively be urged by their overlying pins into punching engagement with the work, and each said projection being spaced at regularly varying distances from the tops of the punches so that upon upward movement of the punch block the punches in the array will successively be lifted by said ledge from the work.

2. In a punching apparatus, a punch structure comprising, in combination, a punch block having a ledge, an array of punches slidably mounted in said block adjacent said ledge so that each punch may reciprocate into said block, means for limiting upward movement of the punch relative to the block, each of said punches having a laterally projecting pin to engage said ledge and thus limit downward movement of the punch relative to the block, said punches being of regularly varying length so that upon downward movement of the punch block the punches in the array will successively be urged by said means into punching engagement with the work, and each pin being spaced at regularly varying distances from the tops of the punches so that upon upward movement of the punch block the punches in the array will successively be lifted by said ledge from the work.

3. In a punching apparatus, a punch structure comprising, in combination, a punch block, an array of punches slidably mounted in said block so that each punch may reciprocate into said block, means for limiting upward movement of the punch relative to the block, each of said punches having a laterally projecting pin, means

5 on said punch block for engaging said pin to limit downward movement of the punch relative to the block, said punches being of regularly varying length so that upon downward movement of the punch block the punches in the array will successively be urged by said limiting means into punching engagement with the work, and each pin being spaced at regularly varying distances from the tops of the punches so that upon upward movement of the punch block the punches in the array will successively be lifted by said engaging means from the work.
